CLAIM

The ornamental design for a watch body mechanical connection, as shown and described.

DESCRIPTION

FIG. 1 is a front perspective view of a watch body mechanical connection according to our new design;

FIG. 2 is a rear perspective view thereof;

FIG. 3 is a front plan view thereof;

FIG. 4 is a back plan view thereof;

FIG. 5 is a right side view thereof;

FIG. 6 is a left side view thereof;

FIG. 7 is a top plan view thereof; and,

FIG. 8 is a bottom plan view thereof.

The broken lines (including, for example, the buttons, connection ports, and the mask pattern feature) illustrate environmental structure and form no part of the claimed design.
